UNITED STATES PATENT OFFICE.

WILLIAM J. DAVIDSON, OF RONALD, VIRGINIA, ASSIGNOR OF TWO-THIRDS
TO ROBERT E. HATCHER AND CHARLES L. HATCHER, OF SAME PLACE.

WASHING-MACHINE.

SPECIFICATION forming part of Letters Patent No. 394,913, dated December 18, 1888.

Application filed March 10, 1888. Serial No. 266,864. (Model.)

To all whom it may concern:

Be it known that I, WILLIAM J. DAVIDSON, a citizen of the United States, residing at Ronald, in the county of Montgomery and 5 State of Virginia, have invented certain new and useful Improvements in Washing-Machines, of which the following is a specification.

This invention relates to washing-machines 10 of that class in which a reciprocating pounder or compress is employed; and it consists in certain improvements in the compress itself and the way of mounting the same, whereby it adjusts itself to the mass of clothing being 15 washed.

My invention also consists of a novel means 20 for holding properly in place a tub or vessel containing the clothes being operated upon, all of which improvements will be hereinafter 25 pointed out, and are illustrated in the accompanying drawings, wherein—

Figure 1 is a perspective view of a washing machine or apparatus embodying my inventions. Fig. 2 is a central longitudinal section, and Fig. 3 is a bottom view of the compress-plate.

A designates the platform or bench, upon 30 which is supported the washing apparatus, and from which projects upward a standard, 35 B, near one end thereof, having pivoted in its upper end the operating-lever C. This standard is braced by an inclined bar, B', and has its upper end forked to permit the pivoted end of the lever C to be adjusted, there being a series of apertures, b, to receive the 45 pivot-pin c.

D is the bar or link by which the compress 50 or pounder E is connected with the operating-handle. The upper end of the bar or link 40 is forked and provided with a series of apertures, d', to permit adjustment thereof upon the lever C, which is done by changing the pivot-pin d from one to another of the apertures, as the quantity of clothes being operated 55 upon in the tub F or other circumstances may require. The lever C is provided with a horizontal slot, c', to receive the pivot-pin d, so as to permit a limited amount of longitudinal movement of the compress and 60 its bar or link, in order to accommodate them to the position of the tub without requiring

separate adjustment each time the position of the tub is changed. The lower end of the link is also forked or slotted, as at g', to receive a cross-bar, G, which is pivoted thereto 55 at g and has a limited rocking movement upon its pivot. To the under face of this bar G the compress E is loosely secured by means of flexible connections, preferably the cords h, which pass through apertures in the 60 plate of the compress and are attached to the bar. This allows the compress-plate to rock upon the lower face of the bar G, in order to accommodate itself to the position of the clothes in the tub. 65

The compress may be made of any suitable material, although I prefer to use a circular wooden plate for that purpose. This plate is preferably formed of two or more sections, e, 70 united to each other by flexible connections, as the cords k, as I have found that the limited amount of flexibility given the compress by forming it of two or more separate pieces is very advantageous, as it better accommodates itself to the inequalities of the mass of 75 clothing being operated upon.

When the compress is made of two or more sections, I prefer to employ a slat, I, of thin material on the under side of the compress-plate, extending transversely across the line 80 of division between the separate sections, as otherwise there is danger of too great yielding or freedom of movement between the separate sections. This slat also tends to prevent splitting of the sections e of the compress- 85 plate to which it is connected by the cords h.

i are stout cords—one on each side of the bar G—secured to the standard, preferably to the upper forked portion below the series of apertures d', and having their opposite strands 90 passing through apertures i' near the edges of the compress, upon opposite sides of the pivot g. These cords, while they permit the compress to rock upon the cross-bar G at right angles thereto, prevent too great freedom of movement thereof, and are adjustably connected at their upper ends to the standard, as by tying or otherwise, so that the tension upon the cords may be varied as circumstances may require. 95

When large articles—such as bed-spreads, table-cloths, and the like—are being washed,

it is often desirable that they should be moved up and down with the compress. This I can insure by passing portions of such articles being washed between the plate E and the 5 looped portions of the cords *i* below the plate.

The above-described device has a universal movement which permits the compress to accurately adjust itself to the position of the tub and the articles therein being washed. 10 The cords by which the parts of the compress are connected, while permitting this freedom of movement, yet so far tend to limit it as to prevent undue looseness of parts.

My compress is so constructed that the 15 washing of clothes is done chiefly by compression, and the clothes in the tub are kept in a compressible condition by always having sufficient water in the tub to partly float the clothes—the more clothes the more water, and 20 vice versa.

I have shown in connection with my device an improved means for holding a tub or other vessel containing the clothes securely in place in proper position upon the bench. It consists of two or more hooks, L, adapted to engage with the upper edge of the tub upon opposite sides thereof, and carried by the cords M, which are secured at one end to the bench and at their opposite ends to a lever, N, which 25 in this instance I have shown as consisting of a treadle-plate having one end resting below the bench and the other end extended beyond the edge thereof to receive the foot of the operator. By pressing downward upon the plate 30 or lever the cords will be tightened and the hooks drawn downward, thus securing the tub in place.

I claim—

1. In a washing-machine, a compress consisting of a plate formed of separate sections 40 flexibly connected together and loosely connected to the supporting-link, substantially as described.

2. In a washing-machine, a compress consisting of a plate formed of separate sections 45 loosely connected, in combination with a slat, I, arranged below the sections of the plate, to which it is loosely connected, substantially as described.

3. In a washing-machine, the combination, 50 with the bar or link and the compress carried thereby, of the cords *i*, secured to the bar or link and passing through apertures in the compress to form looped portions below the compress, substantially as described. 55

4. In a washing-machine, the combination, with the link and the compress carried thereby to have a rocking motion relatively thereto, of the cords *i*, secured at their ends to the link and passing freely through apertures on the 60 opposite sides of the rocking line of the compress, substantially as described.

5. The combination, with the tub, of a hook adapted to engage with the upper edge thereof, a cord secured to said hook, and a lever 65 to which the cord is attached, adapted to draw downward the hook, substantially as described.

In testimony whereof I have signed my name to this specification in the presence of two 70 subscribing witnesses.

WILLIAM J. DAVIDSON.
